Figure 1

Figure 2

Figure 3

FIG. 1 is a front and right side perspective view of a data terminal housing showing our new design, the left side not shown being identical;

FIG. 2 is a front elevational view thereof;

FIG. 3 is a rear elevational view thereof.

The dominant feature of our design resides in the peripheral slot formed by dual lips at the base of the particular housing configuration shown.

This is a continuation of application Ser. No. D127,078, filed Mar. 22, 1971.

We claim:

The ornamental design for a data terminal housing, as shown and described.
